DESIGN FOR A VEHICLE MOUNTED CRANE WITH LOAD ARM ACCESSORY

Robert C. Shoemaker, Portland, Oreg., assignor
to Hyster Company, Portland, Oreg., a corpora-
tion of Oregon

Application December 29, 1944, Serial No. 117,144

Term of patent 14 years

(Cl. D14—3)

To all whom it may concern:

Be it known that Robert C. Shoemaker, a citizen of the United States, residing at Portland, in the county of Multnomah and State of Oregon, has invented a new, original, and ornamental Design for a Vehicle Mounted Crane with Load Arm Accessory, of which the following is a specification, reference being had to the accompanying drawings forming part thereof.

Fig. 1 is a front perspective view of a vehicle

mounted crane with load arm accessory showing my new design;

Fig. 2 is a side elevational view; and

Fig. 3 is a view in perspective, taken from the rear and right side.

I claim:

The ornamental design for a vehicle mounted crane with load arm accessory, as shown.

ROBERT C. SHOEMAKER.
